DESIGN FOR A ROCKING HORSE OR THE LIKE

Cecil C. Cash, Glen Ellyn, Ill., assignor to Montgomery Ward & Co., Incorporated, Chicago, Ill., a corporation of Illinois

Application May 22, 1940, Serial No. 92,523

Term of patent 7 years

To all whom it may concern:

Be it known that I, Cecil C. Cash, a citizen of the United States, residing at Glen Ellyn, in the county of Du Page and State of Illinois, whose post office address is 715 Kenilworth Avenue, Glen Ellyn, Illinois, have invented a new, original, and ornamental Design for a Rocking Horse or the like, of which the following is a specification; reference being had to the accompanying drawing, forming a part thereof.

In the drawing:

I claim:

The ornamental design for a rocking horse or the like, substantially as shown.

CECIL C. CASH.
